UNITED STATES PATENT OFFICE.

ARNOLD NEUHAUS, OF LONDON, ENGLAND.

COMBINED CIGAR-LIGHTING AND ADVERTISING APPARATUS.

SPECIFICATION forming part of Letters Patent No. 468,452, dated February 9, 1892.

Application filed March 28, 1890. Serial No. 345,800. (No model.) Patented in England January 30, 1890, No. 7,220.

To all whom it may concern:

Be it known that I, ARNOLD NEUHAUS, wine and spirit merchant, a citizen of the Republic of Switzerland, residing at London, in the county of London, England, have invented certain new and useful Improvements in a Combined Cigar-Lighting and Advertising Apparatus, (for which I have previously obtained Letters Patent in Great Britain, dated January 30, 1890, No. 7,220,) of which the following is a full, clear, and exact description.

This invention relates to improvements in a combined cigar-lighting and advertising apparatus, and has for its object means for exposing to view a fresh advertisement or advertisements each time the apparatus is used for lighting a cigar.

In carrying out my invention the advertisements are arranged upon the periphery 20 of a drum or drums carried upon a horizontal shaft capable of revolving within a closed casing provided with apertures in front of each advertising-drum, which apertures permit of only one advertisement being visible 25 at a time. The said drum or drums is or are operated by suitable ratchet mechanism actuated by means of a movable arm upon the latter being pulled down from a vertical to a horizontal position. Upon the release of the 30 said arm it returns to its original vertical position by means of a coiled spring.

In constructing a single apparatus or one in which only one advertisement-drum is used I adopt the following arrangement, 35 viz: The drum is provided with, say eight advertisements and is fixed to a horizontal shaft capable of rotation within a casing. This shaft is rotated by means of a ratchet-wheel fixed thereto and having eight teeth. A second shaft parallel with the first-named one is 40 also mounted in the back part of the casing and is provided with an arm or crank, to which is pivoted a weighted pawl engaging with the teeth of the aforesaid ratchet-wheel. To 45 this second shaft is also fixed another arm or crank. In the upper part of the casing is mounted a third horizontal shaft parallel with the advertising-drum, and centrally lengthwise of this shaft is fixed the end of a tubular 50 arm working radially in a slot formed in the casing when pulled down from a vertical to a horizontal position. The other end of this

arm carries a small gas-burner provided with a draft-cup, and in the body of the said arm is a loose valve so arranged that when the 55 arm is in a vertical position the said valve nearly cuts off the gas, only permitting a very small quantity to pass sufficient to maintain a very small flame, but upon the arm being pulled down into a horizontal position the said valve 60 will shift and allow more gas to pass, so as to give a good flame for lighting a cigar or pipe. Upon being released the arm returns to its vertical position by the action of a coiled spring fixed to the aforesaid third 65 shaft. On this third shaft there is fixed an arm or crank immediately over and parallel with the arm or crank fixed near the center of the under or second shaft, and these arms or cranks are connected together by 70 means of a connecting-rod, and thus upon pulling by means of a ring or handle the arm from the vertical to a horizontal position a partial revolution is given to the second and third shafts and an eighth of a revolution 75 to the ratchet-wheel and advertising-drum, thus exhibiting a fresh advertisement to view. Upon the arm being released and returned to the vertical position by means of the aforesaid coiled spring the pawl engages with the 80 next tooth of the ratchet-wheel ready for the next operation. Spring friction-washers are placed on each side of the advertising-drum to prevent vibration and insuring the requisite revolution only of the drum. The gas is 85 conducted to the burner by a piece of india-rubber tubing attached to the end of the arm and to the end of a small supply-pipe passing through the casing.

In constructing a double-advertising apparatus, or one having two drums exhibiting two advertisements at the same time, the said drums are fixed to a horizontal shaft, so as to leave a space between them, and are inclosed in a casing similar to that described with reference to the single drum device, but having two openings for exhibiting the advertisements instead of one. Against the end of one of the drums and in the space between them is fixed to the shaft the ratchet-wheel for 95 operating the drums. A bracket is fixed to the back of the casing centrally between the drums, and is formed with projecting sides, which assist in supporting the shaft carrying 100

the drums, and also carry a short horizontal shaft parallel with the drum-shaft. This shaft is fitted with a gas-light or other arm, a coiled spring, and a crank similar to that described in reference to the single drum arrangement; but according to this device one of the shafts and its crank and the connecting-rod joining it with the other crank may be dispensed with and the weighted pawl be pivoted to the crank on the short shaft, which pawl engages directly with the teeth of the ratchet-wheel, and in order that my said invention may be more fully understood I will describe the same with reference to the accompanying drawings, in which--

Figure 1 represents in front elevation a single drum apparatus. Fig. 2 is a longitudinal section thereof, and Fig. 3 a cross-section.

20 *a* is the drum provided with advertisements on its periphery and fixed to a shaft *b*, capable of revolving in a casing *c*, provided with an aperture *c'*. *d* is the ratchet-wheel fixed to the shaft *b*, into which gears a weighted 25 pawl *e*, pivoted to a crank *e'*, fixed to a second shaft *f*. To the shaft *f* is also fixed another crank *g*. A third shaft *h* is mounted in the upper part of the casing and has fixed to it the end of a tubular arm *i*, which works upon 30 being pulled down in a slot *j*, formed in the casing. The arm *i* carries a small gas-burner *k*, provided with a draft-cup *l* and also a loose valve *m*, which regulates the amount of gas fed to the burner, according to the position of 35 the arm. On the shaft *h* is fixed a crank *n* immediately above the crank *g*, and these two cranks are connected by a rod *o*. Upon the operator pulling by means of the ring or handle *v* the arm *i* from its vertical to a horizontal 40 position the pawl *e* actuates through the ratchet-wheel *d* the shaft *b*, so as to revolve the drum *a* a part of a revolution sufficient to expose one of the advertisements to view, and upon the arm *i* being released it is brought 45 back to its vertical position ready for another stroke by means of the coiled spring *p*, acting on the shaft *h*. Spring friction-washers *q* are placed at each end of the drum to prevent the latter revolving too far. *r* is an in- 50 dia-rubber tube for conducting gas to the burner, being attached to the lower end of the

arm *i* and also to the end of a small supply-pipe *s*, passing through the casing.

Figs. 4, 5, and 6 show my invention applied to a double-advertising drum arrangement of 55 apparatus, in which the aforesaid shaft *h*, crank *g*, and connecting-rod *o* are dispensed with. A bracket *p* is fixed to the back of the casing and has projecting sides *p'*, which support the central part of the drum-shaft. This 60 bracket carries a small shaft *q*, upon which are fixed the weighted pawl *r* and a coiled spring *s'*. The pawl *r* engages directly with the teeth of the ratchet-wheel *e*, and the spring *s'* pulls back the arm *i* to its vertical position 65 upon its being released.

Having thus particularly described and ascertained the nature of my said invention and in what manner the same is to be performed, I declare that what I claim is—

70 1. In a combined cigar-lighting and advertising apparatus, the combination of the revolving drum or drums *a*, provided with advertisements, the shaft *b* for revolving the same, the casing *c*, having apertures *c'*, the ratchet-wheel *d*, fixed to the shaft *b*, the weighted pawl *e* for operating the wheel *d*, shaft *f*, cranks *e'* and *g*, fixed thereon, the pawl *e* being pivoted to the former, shaft *h* in the upper part of the casing, tubular gas-light arm *i*, fixed thereto, spring *p* on shaft *h*, crank *n* on same shaft, and rod *o* for connecting cranks *g* and *n*, substantially as described, and illustrated in the accompanying drawings.

75 2. In a combined cigar-lighting and advertising apparatus, the combination of the drum or drums *a*, provided with advertisements, shaft *f*, cranks *e'* and *g*, fixed thereon, the pawl *e* being pivoted to the former, shaft *h* in the upper part of the casing, tubular gas-light arm *i*, fixed thereto, spring *p* on shaft *h*, crank *n* on same shaft, rod *o* for connecting cranks *g* and *n*, and a burner *k* and movable valve *m* in said arm *i* for regulating the 80 amount of gas passing to the burner.

85 London, March 11, 1890.

ARNOLD NEUHAUS.
